UNITED STATES PATENT OFFICE.

ALBERT N. WIGTIL, OF WALCOTT, NORTH DAKOTA.

GROOVING PLANE.

Application filed July 9, 1921. Serial No. 483,531.

To all whom it may concern:

Be it known that ALBERT N. WIGTIL, a citizen of the United States of America, residing at Walcott, in the county of Richland 5 and State of North Dakota, has invented new and useful Improvements in Grooving Planes, of which the following is a specification.

The object of the invention is to provide a 10 relatively simple and efficient grooving plane adapted to be used in forming either straight walled or under-cut or dove-tailed gains or grooves which are parallel sided or adapted for the reception of tapered keys 15 or wedges and more especially to cut cross grain grooves independently of the use of any other tool except a saw in door window jambs, for key seats, stair treads and the like, and more particularly to cut grooves 20 under conditions in which accuracy in depth and width, and uniformity in dimensions where a number of similar grooves are to be formed may be secured without loss of time or especial measurement from time to time 25 as the work progresses; and with these objects in view the invention consists in a construction and combination of parts of which a preferred embodiment is shown in the accompanying drawings, wherein:—

30 Figure 1 is a perspective view of a grooving plane embodying the invention.

Figure 2 is a transverse sectional view on the plane indicated by the line 2—2 of Figure 1.

35 Figure 3 is a transverse section on the plane indicated by the line 3—3 of Figure 1.

Figure 4 is a longitudinal sectional view on the plane indicated by the line 4—4 of Figure 2.

40 Figures 5, 6 and 7 are detail views of forms of gains or grooves which can be produced by means of the tool.

Figure 8 is a detail elevational view showing the rotatable spindle on one of the 45 handles and its attendant pinion.

Figure 9 is a detail plan view of the cam plate and associated rack and operating pinion, the handle spindle being shown in section.

50 Figure 10 is a detail perspective showing one of the bits or cutters used in connection with the device.

The device consists of a base plate 10 provided with terminal upstanding handles or 55 grips 11 and 12 and having an intermediate clearance opening 13 through which the bit

or cutter 14 extends and operates, the stem 15 of said bit being arranged in an upright guide 16 formed in the guide block 17 and being engaged at its upper threaded portion 60 above the block by gauge nuts 18 and a jam nut 19.

The shank is further provided with a lateral key or lug 20 engaged by a slide plate 21 fitted in a transverse guide 22 in the guide 65 block and provided with a diagonal cam slot 23 for the reception of said lug or key, the slide plate having connection with a rack 24 of which the teeth are engaged by a pinion 25 carried by the spindle 26 of the grip or 70 handle 12 which is revolubly mounted upon the base.

The bit or cutter is preferably tapered or reduced in width from its cutting edge toward the shank or stem and is inclined 75 downwardly from its shank or stem toward its cutting edge with relation to the plane of the under or bearing surface of the base plate as shown clearly in Figure 2.

In preparation for the use of the plane it 80 is only necessary to cut the stock which is to be mortised by means of a saw or like tool to form the walls of the proposed groove, either obliquely as indicated in Figure 5 or square as indicated in Figure 6 and 85 then to set the bit or cutter at a shallow depth with its cutting edge slightly below the plane of the under surface of the base plate and with the set nut disposed at an adjustment on the stem of the bit, in accordance with the graduations thereonto to indicate the depth to which the groove is to 90 be cut, locking the set nut by means of the jam nut. Then as the cutting operation proceeds by the reciprocatory movement of the plane the revoluble handle 12 may be turned slightly after each stroke to feed the bit downward through the agency of the cam slot until checked by the gauge nut. By maintaining a uniform adjustment of 95 the latter it is obvious that a number of grooves of the same depth may be cut successively with an accuracy which is impossible with the use of ordinary tools such as a hand chisel or gouge.

100 In forming a seat such as that shown in Figure 5, the closed end of the groove is formed preferably by a wood bit and the sides defining the groove by the usual saw kerfs, the stock between the kerfs being removed by the plane as in the formation of those shown in Figures 6 and 7.

Having described the invention, what is claimed as new and useful is:—

1. A grooving plane having a base plate provided with manual grips or handles, a bit having a stem mounted in a guide carried by the base plate for movement in a direction perpendicular to the plane of the latter and located in a position between said grips or handle, and means for imparting movement to the bit with relation to the plane of the base plate and consisting of a cam plate having an interlocking sliding engagement with the stem of the bit and rack and pinion operating means for said cam plate, one of said grips or handles being revoluble and said pinion being carried thereby.
2. A grooving plane having a base plate

provided with manual grips or handles and provided with a guide intermediately disposed between said handles, a bit having a stem slidably engaged in said guide and formed with a lateral pin, a cam plate slidably mounted in the guide and having a diagonally disposed slot in which said pin slidably engages, one of said handles being rotatable, and operative connections between said rotatable handle and the cam plate to impart longitudinal movement to the latter and thereby impart vertical movement to the stem to position the bit in the manner specified.

In testimony whereof he affixes his signature.

ALBERT N. WIGTIL.
